TABLE FORK OR SIMILAR ARTICLE OF FLATWARE

John P. Young, Bronxville, N.Y., and Charles A. Arnold, Providence, R.I., assignors to Lyon Incorporated, Detroit, Mich., a corporation of Delaware

Filed Oct. 21, 1959, Ser. No. 58,016

Term of patent 14 years

(Cl. D54—12)

Fig. 1 is a front elevation of a fork showing our new design;

Fig. 2 is an edge elevation of the fork;

Fig. 3 is a rear elevation of the fork;

Fig. 4 is a cross-sectional view taken on line IV—IV of Fig. 1;

Fig. 5 is a cross-sectional view taken on line V—V of Fig. 1; and

Fig. 6 is a cross-sectional view taken on line VI—VI of Fig. 1.

The essential features of our design reside in the handle portion shown in the full lines on the drawing.

We claim:

The ornamental design for a table fork or similar article of flatware, substantially as shown and described.
